YARN CARRIER AND TUBE FOR
KNITTING MACHINES

Frederick Scarborough, Sr., Northampton, Mass.

Application March 1, 1952, Serial No. 274,345

3 Claims. (Cl. 66—126)

1

This invention relates to new and useful improvements in yarn guide means for yarn manipulating machines and more particularly, the present invention has as its primary purpose that of providing a yarn carrier for use on a knitting machine and especially for use on a full-fashioned knitting machine.

As is well-known in the art to which the present invention pertains, the function of such yarn carriers is to supply yarn to the needles of the machine as controlled by the action of the jack sinkers in thrusting the yarn between every second needle when the complete stroke or course of the carrier is completed. The dividers, which are located in the sinkerhead of the machine and positioned between the jack sinkers, are brought forward at the proper moment by operation of the catchbar motion to thereby divide the stitch.

The present invention has as its object to construct a yarn carrier including an elongated arm having special shapings at both its attached end and at its free end with the shaping at the free or front end arranged to support a specially shaped yarn guide tube through which the yarn emerges on its way toward its appointed carriage and constructed in a manner to enable the machine to make a stocking of any gauge.

As a further object, the present invention proposes shaping the yarn guide tube so that its free end is hardly more than a self-sustaining circle in a manner to permit close spacing of the guide tubes of adjacent yarn carriers and shaping of the free end of the arm in a manner to facilitate the required close spacing of the guide tubes.

The present invention further proposes a novel means for removably mounting a tube upon the attached end of the arm in end alignment with the yarn guide tube in a manner to guide the yarn from a source to the yarn guide tube.

It is a further object of the present invention to construct a yarn carrier of the type disclosed which is simple and durable, which is effective in use and which can be constructed and sold at a reasonable cost.

For further comprehension of the invention, and of the objects and advantages thereof, reference will be had to the following description and accompanying drawing, and to the appended claims in which the various novel features of the invention are more particularly set forth.

On the accompanying drawing forming a material part of the present disclosure:

Fig. 1 is a top perspective view of the yarn carrier of the present invention as it appears when mounted in position on the carrier rod of the knitting machine.

2

Fig. 2 is an enlarged transverse sectional view of the attached end of the yarn carrier taken on the line 2—2 of Fig. 1.

Fig. 3 is an enlarged detailed plan view of the free end of the yarn carrier.

Fig. 4 is a transverse sectional view taken on the line 4—4 of Fig. 3.

Fig. 5 is a perspective view of the yarn guide tube, per se.

10 Fig. 6 is a detailed plan view of the arm of the yarn carrier, per se.

The yarn carrier, according to the present invention, is to be mounted in position upon one of the usual carrier rods 10 of a knitting machine, as shown in Fig. 1. The relationship of such carrier rods to the sinkers and needles of a full-fashioned knitting machine is readily known by those versed in the art to which the present invention pertains and, therefore, further details

20 of the machine are not being given in this disclosure as they form no part of the present invention. Details of the construction of the machine and the relationship of the yarn carriers can be obtained from U. S. Patent No. 2,198,081, granted on April 23, 1940, to Gustav Gastrich, and from the pamphlet "Full Fashioned Knitting Machines" published by the Textile Machine Works of Reading, Pennsylvania.

The yarn carrier of the present invention includes an elongated arm 11 having a rectangular rear end portion 11^a and forwardly of that rear end portion, the arm tapers to a front end portion 11^b of reduced width. The rear end portion 11^a is provided to be positioned flat on the top face

35 of the carrier rod 10, see Fig. 1. Where the arm 11 extends beyond the carrier rod 10, it is formed with a smoothly rounded bend 12 to extend away from the rod 10. Slightly inward of the front end portion 11^b, the arm 11 is formed with a reverse smoothly rounded bend 14 so that the front end portion 11^b extends back to the plane of the carrier rod and toward the needles of the machine.

40 Immediately forward of the bend 12, the arm 11 is formed with an aperture 15 of relatively large dimensions and forward of the aperture 15, the arm 11 has a second smaller aperture 16. The apertures 15 and 16 are arranged on the longitudinal axis of the arm 11, see particularly Fig. 6.

45 Between the aperture 15 and the rear edge of the rear end portion 11^a, the top face of that rear end portion is formed with a shallow groove 17, see Figs. 2 and 6. The groove 17 is formed

50 on the longitudinal axis of the arm 11 and is provided for seating a tube 18 on the longitudinal

axis of the arm 11. Extended laterally across the rear end portion of the arm 11, there is a clamp strip 19 formed intermediate of its ends with a upwardly rounded portion 20. The upwardly rounded portion 20 is provided for snugly fitting over the top of the tube 18 where it extends from the groove 17, as best shown in Fig. 2. The clamp strip 19 on opposite sides of the upwardly rounded portion 20 is formed with holes 21 aligned with complementary holes 22 formed in the rear end portion of the arm 11 on opposite sides of the groove 17. Screws 23 having washers 24 beneath their heads, are passed freely through the aligned holes 21 and 22 and threaded into complementary holes 25 formed in the carrier rod 10. Thus, the screws removably attach the rear end portion 11a of the arm 11 to the carrier rod 10 and mount the clamp strip 19 in a fixed position in which the tube 18 is held in position in the groove 17. By slightly loosening the screws 23, the tube 18 can be slipped from beneath the upwardly rounded portion 20 of the clamp strip 19 to be replaced by a new tube without requiring complete removal of the yarn carrier from the carrier rod 10.

The rear end of the tube 18 has an outwardly flared portion 18a for facilitating threading of the yarn from a source through the tube 18 and from the tube 18 to a yarn guide tube 26 supported upon the front end portion 11b of the arm 11. Intermediate of its ends, the yarn guide tube 26 is formed with an integral stop block 27 which divides the tube 26 into a rear mounting portion 26a and a front end portion 26b.

The front end portion 11b of the arm 11, forwardly of the bend 14 is formed with an aperture 28. Forwardly of the aperture 28, the front end of the arm 11 is formed with a notch 29 of a size to snugly receive the stop block 27 of the yarn guide tube 26 to hold the tube against rotation. The material of the front end portion of the arm 11 between the aperture 28 and the notch 29, is formed with a bore 30 of a diameter slightly smaller than the outside diameter of the rear mounting portion 26a of the yarn guide tube 26. Parallel with the bore 30 and traversing the bore, the arm 11 between the aperture 28 and the notch 29 is formed with a slit 31. The slit 31 permits the material of the front end portion 11b on opposite sides of the slit to spread apart as the rear mounting portion 26a of the yarn guide tube 26 is forced into the bore 30, as shown in Fig. 3. Inward insertion of the rear mounting portion 26a is stopped when the stop block 27 strikes the material of the arm 11 defining the inner edge of the notch 29.

The free end of the front end portion 26b of the yarn guiding tube 26 is cut off at an oblique angle which extends downward and rearward. The yarn from the source after leaving the front end of the tube 18, passes through the aperture 15 then along the bottom face of the arm 11 to the aperture 16 and then along the front face of the arm 11 to the upper end of tube 26. The

yarn enters the upper end of the yarn guide tube 26 passing therethrough and from the front end of the yarn guide tube to the sinkers and needles of the knitting machine as is generally known in the art.

The formation of the end of the front end portion 26b of the yarn guide tube 26 forms a taper 32, see Fig. 5, at the front or lower end of the tube from which the yarn emerges on its way to the appointed needle of the machine, as already stated. Thus, the front or lower end of the yarn guide tube 26 is hardly more than a self-sustaining circle so that the yarn carriers required by a single machine can be mounted with their arms and yarn guide tubes placed very close together and yet without giving rise to the heretofore-encountered troubles and dangers relative to wear, breaking and mutual entanglement of adjacent yarn lengths and even breakage of the ends of the arms and yarn guide tubes themselves.

While I have illustrated and described the preferred embodiments of my invention, it is to be understood that I do not limit myself to the precise constructions herein disclosed and the right is reserved to all changes and modifications coming within the scope of the invention as set forth in the appended claims.

Having thus described my invention, what I claim as new and desire to secure by United States Letters Patent is:

1. A tip for mounting on the front end portion of a yarn carrier mounted on a knitting machine comprising, an elongated arm, said arm having a rectangular rear portion and a tapered front end portion; said front end portion having a bore therein, a notch in the forward edge of said tapered front end, and a guide tube extended into said bore and carrying a stop block, said block engaging in said notch to prevent further rearward movement of said guide tube and to prevent rotation thereof.

2. The device of claim 1 wherein said notch is rectangular in shape and said stop comprises a complementary rectangular member.

3. The combination of claim 2 wherein said bore includes an elongated slit to permit slight separation of the front end portion as the tube is inserted.

FREDERICK SCARBOROUGH, SR.
